UNITED STATES PATENT OFFICE.

ALBERT G. SCHERER, OF CHICAGO, ILLINOIS, ASSIGNOR TO EXCELSIOR STEEL FURNACE COMPANY, OF CHICAGO, ILLINOIS, A CORPORATION OF ILLINOIS.

HOT-AIR STACK.

1,175,306.

Specification of Letters Patent.

Patented Mar. 14, 1916.

Application filed August 10, 1912. Serial No. 714,351.

To all whom it may concern:

Be it known that I, ALBERT G. SCHERER, a citizen of the United States, and a resident of Chicago, in the county of Cook and State 5 of Illinois, have invented certain new and useful Improvements in Hot-Air Stacks, of which the following is a specification.

Hot air stack is employed for conveying hot air from a central plant or furnace to 10 various portions of a building, and the present practice is to conceal it as much as possible, within the walls; and, on account of this practice, the stack is almost universally made of rectangular cross-sections so as to 15 adapt it for installation between the stud- 60 ing, and at the same time secure the greatest cross-sectional area or capacity for carrying the air. Such stack is made of sheet metal with either double or single walls, the 20 meeting edges of the necessary blanks of sheet metal being provided with reverse bends, which when assembled are pressed together thereby forming a joint the 25 strength of which depends upon the thick- 65 ness and toughness of the metal employed. Such stack, made in the usual manner, as 30 above described, and having a rectangular cross-section, has little resistance to strains which tend to compress it; and, I have 35 found that in both shipment and installa- 70 tion it has been so compressed, and the joints have been disengaged and the stack opened.

The object of my present invention is to 35 stiffen the construction of such stack genera- ally, and so form the seam or seams that 40 they will not become disengaged and opened whether the pipe be compressed or not.

I attain the above objects by means of the 45 construction illustrated in the accompany- 40 ing drawing, in which—

Figure 1 is a perspective of a section of 50 hot air stack embodying my present invention; Fig. 2 is a section on line 2—2 of Fig. 1; Fig. 3 is an enlarged fragmental section 45 across the seam on line 3—3 of Fig. 1; and Fig. 4 is a view similar to that of Fig. 3 upon line 4—4 of Fig. 1.

Similar reference characters refer to simi- 55 lar parts throughout the several views. The reference characters 1 and 2 designate respectively opposite broad sides of a section of rectangular hot air pipe which is formed of two sheets of metal, each of which are bent at right angles a suitable distance 55 from their longitudinal edges to form the

shorter sides or edges, 3 and 4, of a section of stack. The meeting edges of the respective sheets of metal are provided with the reverse engaging bends, 5 and 6, in the usual manner, as clearly shown in Fig. 3. 60

When double-wall pipe is made, as shown in Figs. 1 and 2, a precisely similar plan of construction is followed upon slightly smaller cross-sectional dimensions. I have designated similar parts of the inner wall 65 with similar characters to which the prime mark has been added. Certain provisions, 7, for assembling the respective sections with each other and means for maintaining the spaced relation of the inner and 70 outer walls are provided, but these form no part of my present invention, and need not be described.

With stack made in the usual way, as 75 above described, the engaging reverse bends, 5 and 6, are compressed by a press or in any suitable manner, and it is these joints that are disengaged and forced open by compression of the stack, as above noted. In 80 stack so made the three additional layers of metal at the seams form the ridge, or shoulder or seam, 9, which is usually thrown upon the outside of the stack. Now, in order to prevent the disengagement of this seam, I 85 force, for short distances at suitable intervals, the shoulder 9 inwardly so that the outer surface thereof is substantially flush with the outer surface of the stack, and the seam projects on the inside of the stack, as 90 shown at 10 in Fig. 1 and in Fig. 4 viewed in connection with Fig. 3. This results in a 95 stiffening of the entire stack, and prevents the disengagement of the reverse bends 5 and 6 by any pressure which would not be sufficient to wreck the entire structure. 95

Having described my invention, what I claim as new and desire to secure by Letters Patent, is:—

1. A hot air stack of rectangular cross-section comprising a plurality of sheets of 100 metal bent at right angles to form, when assembled, a conduit of rectangular cross-section, the meeting edges of said sheets being provided with engaging folds, said folds being compressed into a ridge, and separated 105 and elongated sections of said ridge being forced to the side of the wall of each stack opposite to the side upon which the ridge was originally formed.

2. A double walled hot air stack of rec- 110

tangular cross-section, comprising a plural-
ity of sheets of metal bent at right angles to
form, when assembled, a double walled con-
duit of rectangular cross-section, the walls
5 whereof are spaced apart, the meeting edges
of said sheets being provided with reverse
engaging folds, said folds being compressed
into a ridge, and separated elongated sec-
tions of said ridge being forced to the side

of the wall of each stack opposite to the side 10
upon which the ridge was originally formed.

In testimony whereof I have hereunto set
my hand in the presence of two witnesses.

ALBERT G. SCHERER.
